UNITED STATES PATENT OFFICE

164,562

WALL PLAQUE FOR SALT AND PEPPER SHAKERS

Theodore L. Feinberg, Chicago, Ill.

Application February 13, 1951, Serial No. 14,203

Term of patent 3½ years

(Cl. D44—29)

To all whom it may concern:

Be it known that I, Theodore L. Feinberg, a citizen of the United States and a resident of Chicago, Illinois, have invented a new, original, and ornamental Design for a Wall Plaque for Salt and Pepper Shakers, of which the following is a specification, reference being had to the accompanying drawing, forming a part thereof.

In the drawing:

Figure 1 is a perspective view of a wall plaque for salt and pepper shakers, showing my new design;

Figure 2 is a top plan view; and

Figure 3 is a bottom plan view thereof drawn to a somewhat smaller scale.

I claim:

The ornamental design for a wall plaque for salt and pepper shakers, substantially as shown.
THEODORE L. FEINBERG.
